UNITED STATES PATENT OFFICE

96,043

DESIGN FOR A SHOE HEEL

Fred C. Lovejoy, St. Louis, Mo., assignor to United Shoe Machinery Corporation, Paterson,
N. J., a corporation of New Jersey

Application May 17, 1935, Serial No. 56,880

Term of patent 14 years

To all whom it may concern:

Be it known that I, Fred C. Lovejoy, a citizen of the United States, residing at St. Louis, in the State of Missouri, have invented a new, original, and ornamental Design for a Shoe Heel, of which the following is a specification, reference being had to the accompanying drawing, forming part thereof.

The drawing is a perspective view of a shoe heel
embodying my new design.

What I claim is:

The ornamental design for a shoe heel, as shown.

FRED C. LOVEJOY.
